UPHOLSTERY MACHINE

Cecil Anderson Boyd, Rochester, Mich., assignor
to Briggs Manufacturing Company, Detroit,
Mich., a corporation of Michigan

Application February 18, 1938, Serial No. 191,161

3 Claims. (Cl. 112—2)

This invention relates to a method of securing cloth or fabric to trim panels, such for instance, as the application of upholstery cloth or trim fabric to relatively stiff fiber board panels used for the interior trim of door and body panels of motor vehicle bodies. In one of its aspects the invention contemplates providing an improved machine for performing the operations contemplated by said method.

The present practice commonly employed in the above art is to perform some of the operations of this general character with the use of conventional sewing machines utilizing a manual feed of the trim panel materials. However, such a practice has a number of serious disadvantages. Manual operation of the sewing machine and manual manipulation of the parts under high production conditions, and assembling together by hand the cardboard panels, pieces of felt padding, cloth fabric, fiber strips and the like, kept unfastened until they are sewn together, has proved to be a very difficult operation. It has required a considerable number of operators to work in close proximity to the machine, in consequence whereof large panels handled in a small space produce confusion and disorder in the department. In addition, the assembled pieces become very easily displaced either before getting into the machine or during the actual process of sewing, which results in high percentage of scrap, frequent stops, low production and waste of labor and material.

One of the objects of the present invention is to provide an improved method of securing fabric to upholstery material to a cardboard panel or the like used for interior trim of motor vehicles, whereby a simpler, less expensive trimming of improved appearance is produced.

Another object of the invention is to provide an improved machine for performing the operations contemplated by the above method, means being provided for feeding the machine automatically at a predetermined rate of speed, whereby the machine is caused to operate at its capacity for long periods of time.

Still another object of the invention is to provide an improved machine for performing the operations contemplated by my improved method, said machine being provided with means whereby the parts entering into the structure are assembled quickly and accurately in a predetermined mutual spaced relation and with a minimum of manual labor, whereby a faster and a more dependable production is insured, and the space in the plant is more economically utilized.

A further object of the invention is to provide an upholstery sewing machine in which there are provided improved means whereby the assembled pieces of work are tightly and securely held together during the feeding thereof to the machine and during the process of sewing, whereby the displacement of such pieces is prevented.

A still further object of the invention is to provide an improved upholstery sewing machine in which there are provided means whereby bulging of the cloth or fabric on the cardboard panels is greatly minimized.

It is an additional object of the present invention to provide an improved upholstery machine of the foregoing character, which is relatively simple in construction, rapid and serviceable in use, and inexpensive to build and service.

Other objects of this invention will appear in the following description and appended claims, reference being had to the accompanying drawings forming a part of this specification wherein like reference characters designate corresponding parts in the several views.

Fig. 1 is a perspective view of the upholstery machine constructed in accordance with one embodiment of the invention and viewed from the receiving or feeding end of the machine.

Fig. 2 is a perspective view of the same machine from the delivery end thereof.

Fig. 3 is a perspective view of the machine on an enlarged scale, illustrating particularly the stitching mechanism and the end of the conveyor adjacent thereto at the feeding side of the stitching mechanism.

Fig. 4 is another perspective view of the machine from the delivery end thereof.

Fig. 5 is a transverse sectional view taken on the line 5—5 of Fig. 3, looking in the direction of the arrows.

Fig. 6 is a transverse sectional view through the delivery end of the upper conveyor, the section being taken on the line 6—6 of Fig. 2, looking in the direction of the arrows.

Figs. 7, 8, 9, 10 and 11 illustrate the steps of upholstering the upper part of a door panel in accordance with my improved method, which steps may be done with the aid of the machine herein disclosed.

Figs. 12, 13, 14, 15 and 16 are fragmentary sectional views taken through the seam of the door panel, the sections being taken on the lines 12—12 of Fig. 7, 13—13 of Fig. 8, 14—14 of Fig. 9, 15—15 of Fig. 10 and 16—16 of Fig. 11 respectively.

Before explaining in detail the present inven-

tion it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

In the drawings there is illustrated, by way of example, an improved method of securing pieces of upholstery cloth to substantially rigid panels. In the present instance my improved method is illustrated in application to the process of upholstering the upper part of a cardboard door panel, such as may be used in trimming the interior of a motor vehicle body. However, it will be understood that my improved method may be used with equal success in other connections. In the drawings there is also illustrated, by way of example, an improved continuously operating machine with the aid of which it is possible to perform all the operations contemplated by my improved method.

Figs. 7 to 16 inclusive illustrate the successive steps or the operations included in my method. As illustrated, the method contemplates upholstering the upper part of a cardboard door panel, the lower part whereof has already been upholstered.

In Fig. 7 there is shown a relatively stiff or rigid panel 20 made of cardboard or any other suitable material which panel or foundation sheet is covered with a sheet of padding 21 made of felt, wadding, batting or other suitable material, which sheet is substantially coextensive with the panel 20. The lower part of the padded panel, said part appearing as the upper part in the drawings, is covered with a piece of upholstery cloth 22, said cloth, padding and cardboard panel being secured together in any suitable manner, such as by transverse stitching as indicated at 23.

Figs. 8 and 12 illustrate the first step of upholstering the upper (lower in Fig. 8) part of the panel, which step comprises providing a piece of cloth 24 of the size and shape to cover the portion of the padded sheet 21 remaining uncovered. The sheet 24 is arranged with its lower edge 24a along the edge of the sheet 22 as shown in Fig. 8. It is to be noted that the sheet 24 is laid on the panel with its finished or outer face down and it extends toward the lower (upper in the drawings) edge of the door panel.

The second step is to provide a narrow reinforcing strip 19 made of fiber or any other suitable material, which strip is superimposed on the sheet 24 along the lower edge thereof as illustrated in Figs. 9 and 14.

Thereupon, the reinforcing strip, the cloth piece, the layer of padding and the fiber board panel are stitched through by a line of stitching 19a as illustrated in Figs. 10 and 15. It will be noted that the transverse line of stitching 19a is parallel to but spaced from the line of stitching 23.

The sheet 24 is then turned over to cover the upper portion of the felt covered door panel as illustrated in Figs. 11 and 16, the strip 19 being also bent or folded back upon itself as indicated.

The operations of the above described method may be somewhat changed to suit the particular circumstances and shapes of the parts used in

upholstering the body panel, and they may be performed by hand or with the aid of machines of different types.

I prefer to perform said operations with the aid of my improved machine hereinafter described and illustrated in Figs. 1 to 6 inclusive. With the aid of said machine the cardboard panels and the cloth sheets are fed to a stitching mechanism automatically and continuously, while assembling and the proper alignment thereof is done by an operator standing near the feeding end of the machine.

As illustrated in the drawings, the machine comprises generally a stitching mechanism of any suitable type, and a conveyor moving the cardboard panels toward the stitching mechanism, means being provided for assembling and proper alignment of the panel parts and firm engagement of the assembled units before stitching and feeding them continuously at a predetermined rate of speed to said stitching mechanism.

Referring to the drawings, the machine comprises a table or bed 25 on which there is provided an upstanding frame 26. The stitching mechanism may be of any suitable conventional type, and since the stitching mechanism itself forms no part of the present invention no detailed description thereof is deemed to be necessary, and only a brief description thereof, necessary for a full understanding of the drawings, is given herein. The stitching mechanism consists of two parts: a needle operating mechanism and a looper operating mechanism, said parts being adapted to form a line of stitching in the work moved between them with the feeding means hereinafter described in detail. The needle operating mechanism is supported on the bridge 27, and it includes a mounting or guide block 28 in which there is provided a reciprocating needle bar 29 carrying a needle 30. The reciprocations of said bar 29 are effected by means of an eccentric 31 provided on the shaft 32, which shaft is driven from the main shaft 33 through the vertical shaft 34 drivingly connected with said main and said eccentric shafts with the aid of two bevel gear drives 35 and 36.

The looper operating mechanism is assembled on the lower bridge 37 and the lower member 38 of the upstanding frame 26. The threads are fed to the needle and to the looper from the spools 39 and 40 respectively. Both the needle operating mechanism and the looper operating mechanism may be adjustably moved on their respective bridges and secured thereon in such places as to suit work of some particular dimensions. The looper operating mechanism is actuated by the shaft 41 driven from the main shaft 33 through the vertical shaft 34 and drivingly connected therewith by means of a train of gears including two bevel gears 42 and two spur gears 43 designed to provide the proper gear ratio. The flywheel 44 is provided on the eccentric shaft 31 to insure a smoother operation of the stitching mechanism. Devices 45 are provided in order to effect a proper tension on the thread.

Means automatically feeding the assembled panels to the stitching mechanism comprise, in the present embodiment, a horizontal frame or table 46 in which there is arranged a conveyor comprising a number of resilient connectors, in the present instance two endless feed chains 47 and 48 running on toothed wheels mounted on the driving shaft 49, which shaft is in turn driven from the main shaft 33 through a reduction box 50 and a chain drive 51. At the receiving end

of the conveyor the chains 47 and 48 run on idler gears covered, for reasons of safety, by a guard 52. With the aid of the above described conveyor, the panels which are manually put one by one on the conveyor are continuously moved toward the stitching mechanism.

In order to insure proper positioning of the card-board panels on the conveyor, a gauge bar 53 is provided along the chain 47. The operator standing on the right hand (looking toward the stitching mechanism from the delivery end of the conveyor) side of the conveyor loads the panels, such as shown in Fig. 7, on the conveyor, the edge 54 of the panel being put against the gauge bar 53, see Fig. 5. By virtue of the provision of the gauge bar 53, the panels are thus properly aligned on the conveyor.

Cooperating with the feed chain 47 and effective to assist the same in feeding the panels toward the stitch forming mechanism is a flexible connector such as an endless feed chain 57 upon which is secured a fabric cover belt 57a. The lower course of the belt 57a engages under suitable pressure the upper fabric covered face of the trim panel (Fig. 5). The lower course of the chain 57, hereinafter termed the left pressure chain, is weighted with heavy blocks 58 with the aid of which it is pressed down against the panel for the firm frictional engagement thereof between the feed chains 57 and 47. The chain 57 is driven by the toothed wheel 59 mounted on the shaft 60 driven through a set of gears from the shaft 49. The idler gear 61 provided on the other end of the chain 57 is mounted on the supporting shaft 62 arranged in brackets 63 mounted on the frame 46.

A guide bar 64 is provided along the chain 48 and it extends from the shaft 62, upon which it is mounted at one end, toward the stitching mechanism, its other end being supported by a shaft 65 on which an idler gear 66 of the right pressure member 68 is mounted, Fig. 3. A number of rollers or wheels 69 is provided on the guide bar 64 near the shaft 65. The right pressure feed member 68 comprises a flexible connector such as an endless chain covered with a fabric belt 68a, Fig. 5, and this member runs over a driving toothed wheel 70 mounted on the shaft 60, Fig. 2. The lower course of the belt covered chain 68 is weighted with blocks 68b with the aid of which it is pressed down against the panel for the firm frictional engagement thereof between the feed chains or members 68 and 48. The weight blocks 58 and 68b maintain the feed belts 57a and 68a in proper relation at all times and are held in fixed spaced relation by cross shafts or tie rods 75 and 90 (Figs. 3 and 6). The gear ratio between the shafts 49 and 60 is 1:1 and, therefore, said shafts run at the same rotative speed as well as do the driving toothed wheels of the chains 47, 57, 48 and 58. Therefore, all of said chains move at the same speed and a panel engaged by said chains is moved at a uniform speed and without distortion toward the stitching mechanism.

In operation, as the panels arranged on the chains 47 and 48 reach the left pressure chain 57, the edge 54 of the panel first becomes firmly engaged between the chains 47 and 57, see Fig. 1. The operator places a piece of cloth 24 over the panel, as it moves toward the stitching mechanism, arranging the edge 24a of the fabric blank (Fig. 13) against the guide bar 64. As the panel reaches the right pressure chain 68, it becomes engaged between the chains 68 and 48 and is, therefore, firmly held in its assembled position

and moved toward the stitching mechanism. The rollers 69 engage the panel and prevent bulging up of the cloth as the same is engaged by the right pressure chain 68. The relatively stiff reinforcing tape or strip 19 is unwound and fed from a roll carried by a reel 71 and is guided with the aid of any suitable means to and beneath the presser foot 95 (Fig. 5) whence it is fed to the needle 30 and stitched down at 19a along the edge of the cloth piece, see Fig. 15. The stitched panels are delivered at the delivery end of the conveyor and the cloth piece may be turned over by hand in the manner shown in Fig. 16.

It will be understood that means are provided for starting and stopping the conveyor and the stitching mechanism. In order to hold the cloth firmly in proximity to the needle 30, a hold down chain 72 running over toothed wheels 73 and 74 is provided. The driving wheel 73 is secured on the shaft 65, while the idler wheel 74 is rotatively mounted on the shaft 75 arranged in the pressure blocks 58 and 68b. (See Figs. 3, 5 and 6.) The shaft 75 is bent as indicated at 75a and the bent end may be set at the desired angle with the aid of a set screw 76 to increase or to relieve the pressure on the cloth. A depending bracket 77 carrying rollers 78 is mounted on the bridge 27 and serves to hold the panel down on the other side of the needle 30 (see Fig. 5). Thus it will be seen that the fabric covered panel, the top fabric blank and the fiber binding tape may be accurately guided and fed to the stitch forming mechanism and simultaneously stitched together in predetermined relation.

The above described machine may be used not only for sewing the upper cloth piece as described, but also for sewing the lower cloth piece, which is to say, to bring the panel in the state shown in Fig. 7. The above described machine may also be used for many other sewing operations.

I claim:

1. In an apparatus for attaching fabric material to substantially inflexible paneling material, a longitudinally extending conveyor positioned to receive said material, means to drive the conveyor to move said material forwardly, a gauge bar extending longitudinally of the conveyor and being substantially coextensive therewith and positioned to engage the edge of a piece of said material, a pair of upper conveyor elements, means to drive the upper conveyor elements at substantially the same speed as said conveyor, the upper conveyor elements having their ends which first engage the material staggered longitudinally and cooperating with the conveyor to successively move said material forwardly, a guide bar on the opposite side of the conveyor from the gauge bar and spaced above the conveyor, the guide bar extending longitudinally of the conveyor intermediate the ends of the upper conveyor elements which first engage the material, and means for attaching the fabric material to the paneling material.

2. In an apparatus for attaching fabric material to substantially inflexible paneling, means to attach said fabric material to the paneling material, a main conveyor element to feed material forwardly towards said attaching means, an upper conveyor element positioned above said main conveyor element and so positioned that it lies intermediate the length of said main conveyor element and has its forward end which first engages said material spaced a substantial distance from the end of said main conveyor ele-

ment, a gauge bar extending parallel to said main conveyor element and extending from the forward end thereof to the forward end of said upper conveyor element, a second upper conveyor element engaging said main conveyor element and spaced longitudinally in the line of feed from the point of engagement of the first mentioned upper conveyor element with the main conveyor element, a guide bar spaced laterally from the gauge bar and extending longitudinally of the main conveyor element in the line of feed between the forward end of the upper conveyor element and the forward end of said second upper conveyor element, said guide bar being spaced vertically above the main conveyor element so that a second piece of material can be positioned on the panel while the panel is gripped on the conveyor between the main conveyor element and said upper conveyor element to hold said fabric and panelling materials in a fixed relation relative to said means for attaching the fabric material to the panelling material.

3. In an apparatus for attaching fabric mate-

rial to panelling material, a pair of transversely spaced longitudinally extending conveyor elements positioned to receive said material, means to drive the conveyor elements in unison to move

- 5 said material forwardly, a gauge bar extending longitudinally of the conveyor elements and positioned to engage the edge of a piece of said material, a pair of transversely spaced upper conveyor elements, means to drive the upper conveyor elements at substantially the same speed as said conveyor elements, the upper conveyor elements having their ends which first engage the material staggered longitudinally and cooperating with the conveyor to successively move
- 10 said material forwardly, a guide bar on the opposite side of the conveyor elements from the gauge bar and spaced above the conveyor, the guide bar extending longitudinally of the conveyor intermediate the ends of the upper conveyor elements
- 15 20 which first engage the material, and means for attaching the fabric material to the panelling material.

CECIL ANDERSON BOYD.
